DESIGN FOR A WOODEN FASTENER

Dudley W. Lester, Chicago, Ill.

Application June 24, 1943, Serial No. 110,514

Term of patent 3½ years

To all whom it may concern:

Be it known that I, Dudley W. Lester, a citizen of the United States, residing at Chicago, in the county of Cook and State of Illinois, have invented a new, original, and ornamental Design for Wooden Fastener, of which the following is a specification, reference being had to the accompanying drawing, forming part thereof, in which,—

Fig. 1 is a view in front elevation of a wooden fastener embodying my new design;

Fig. 2 is a view in side elevation taken at right angles to Fig. 1; and

Fig. 3 is a perspective view of the device.

I claim:

The ornamental design for a wooden fastener, substantially as shown.

DUDLEY W. LESTER.
